(57) **CLAIM**

The ornamental design for a fixed pressure regulator for irrigation systems, as shown and described.

DESCRIPTION

FIG. 1 is an isometric view of the fixed pressure regulator; FIG. 2 is an elevation view of the front of the fixed pressure regulator;

FIG. 3 is an elevation view of the side of the fixed pressure regulator.

FIG. 4 is a top plan view of the fixed pressure regulator; and, FIG. 5 is a bottom plan view of the fixed pressure regulator. The broken lines showing of unclaimed portions of the fixed pressure regulator form no part of the claimed design.
